ALBERT D. ANGELL, OF COLDWATER, MICHIGAN.

Letters Patent No. 92,417, dated July 13, 1869.

IMPROVED UTERINE SUPPORTER.

The Schedule referred to in these Letters Patent and making part of the same.

To whom it may concern:

Be it known that I, ALBERT D. ANGELL, of Coldwater, Branch county, State of Michigan, have invented a new and useful Improved Truss and Uterine Supporter; and hereby declare the following to be a full, clear, and exact description thereof, reference being had to the accompanying drawings, making part of this specification.

My invention relates to a construction of truss particularly designed to correct abnormal conditions of the uterus.

A is a pad, preferably of metal, adapted to bear against the lumbar vertebra.

B is a steel bar, proceeding from one end of said pad, and having hinged to it, at C, a second bar, D, curved in continuation of the former, and adapted to be set in or out, by means of set-screws D D'.

The bar D terminates in a block, E, to which two abdominal pads, F F', are secured by pivots f f'.

The opposite end of the pad A to the bar B is provided with an extensible strap, G, having eyelets g, either one of which is engaged over a knob, H, on the block E.

The block E has a stud, e, which engages on one or other orifice, u, of a bar, U, to which is hinged a similar bar, J, which terminates in a sink or basin, K, whose outlet k passes into a screw-neck, L, for the attachment of a sack or pouch, M, of caoutchouc, or other suitable material.

Rising from the sink K, immediately over the outlet, is a tripod, N, having a point, m, which enters at its lower end and supports the hollow stem O of my pessary O P, whose funnel-formed top P, is adapted to receive and support the mouth of the uterus, so as to hold it to its normal position, the hollow stem serving to conduct off all uterine excretions into the sink K and sack M, and to prevent their contact with the walls of the vagina.

The pessary O P is capable of assuming easily any inclined position, so as to cause no restraint, and its interior is lined with silver or gold, so as to avoid irritation.

The bar U, being engaged by its appropriate aperture over the stud e, is secured thereto by a catch, Q.

The opposite end of the sink K to the bar J, has an extensible strap, R, having eyelets r, which engage over a stud, S, at the back of the lumbar pad.

To prevent the strap R drawing inconveniently into the sacral cavity, and causing irritation, I provide

upon said strap a shiftable pad or bag, T, of India rubber, having orifices t t' at its upper part, through which the air can circulate freely, so as to prevent heating.

It will be observed that the pessary can, by shifting of the bar U on the stud e, be elevated or depressed, so as to suit the requirements of the patient.

The sac M having only a small neck, just sufficient to admit the excretions aforesaid, the latter, when once in the sac, are not liable to be spilled or thrown out of the same by various positions of the body.

This instrument is well adapted as a means of rectification of the various abnormal positions of the uterus; thus, for example, for simple *prolapsus uteri*, the pessary may be elevated bodily, by the elevation of the bar U and strap R; for anteversion, the former may be slackened, and the latter tightened; while for retroversion of the uterus, the adjustment is of course reversed.

In practice, I give a slight upward curve to the spring D, so as to escape the crest of the ilium.

Besides the uses already indicated, the sink K and sac M, together with the bar U and strap R, suspended from a girdle, may be made available for the monthly, or catamenial flow, and for leucorrhœa and other vaginal excretions.

The pads F may be attached directly to the spring D, so as to dispense with the block E.

I claim herein as new and of my invention—

1. The adjustable funnel-formed pessary O P, supported loosely on the tripod N m, over the outlet of the sink K, from which depends the narrow-necked sac or pouch M, substantially as described, and for the purposes aforesaid.

2. In combination with the above-named parts, the devices whereby the pessary is made adjustable in height and direction, consisting of the strap R, shifting-bar U, stud e, and catch Q, substantially as described.

3. In combination with the strap R, the shiftable and ventilated rubber bag T, substantially as described, and for the purpose before explained.

In testimony of which invention, I hereunto set my hand.

A. D. ANGELL.
